[57] CLAIM

The ornamental design for a pocket torch, as shown and described.

DESCRIPTION

FIG. 1 is a top, front, left-side perspective view of a pocket torch showing my new design, the adjustable being turned to the front;

FIG. 2 is a top, front, left-side perspective view thereof with the adjustable head being turned to the top;

FIG. 3 is a front elevational view thereof;

FIG. 4 is a rear elevational view thereof;

FIG. 5 is a side elevational view thereof, the opposite side being substantially a mirror image thereof;

FIG. 6 is a top plan view thereof, and

FIG. 7 is a bottom plan view thereof.

The light source is shown in broken lines for illustrative purposes only.
